UNITED STATES PATENT OFFICE.

VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

WOVEN CARRIER.

1,251,891.

Specification of Letters Patent.

Patented Jan. 1, 1918.

Application filed April 23, 1917. Serial No. 163,797.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Carriers, of which the following is a specification, reference being had therein to the accompanying drawings.

10 The invention has relation to woven pocketed carriers. It is applicable especially in the case of carriers on the order of those employed as cartridge carriers, but is not necessarily restricted thereto.

15 The invention consists in an improved pocketed carrier of novel construction, which may comprise either a single pocket or a series of pockets connected together.

20 The object of the invention is to produce a woven pocket having a front and sides which will stand out from the back of the pocket with the required fullness to give the pocket the desired ample internal capacity, and characterized by having a smooth front, 25 free from the puckers, gathers, or wrinkles which commonly exist in the tapering contracted lower portions of pockets made as heretofore.

20 The improved pocketed carrier has a pocket that is formed with the pocket-front integrally joined to the pocket-back at the bottom of the pocket, and united laterally with the pocket-back by means of side-wall web-portions which, as woven, are free at 35 their lower ends. The side-wall web-portions are produced as plain web-strips of the required proportions to permit the pocket-front to stand out from the pocket-back to the extent necessary to secure the desired 40 fullness and capacity of the pocket. The lower portions of the said side-wall web-portions are tucked inwardly between the pocket-front and pocket-back, and are made secure by fastenings, such for instance as 45 stitches.

The drawings illustrate the improved pocketed carrier, and also the method of producing the same.

50 Figure 1 of the drawings is a front elevation of one of the pockets of the said carrier, and its cover-flap, together with adjacent portions of the body-web or band of the carrier.

Fig. 2 is an edge view of the parts that are

shown in Fig. 1, the body-web or band being 55 in vertical section.

Fig. 3 is a front view, with portions broken away, of the parts shown in Figs. 1 and 2, as produced in a loom, without the cover-flap.

Fig. 4 is a bottom view of the parts that are shown in Fig. 3.

In the drawings, 1 designates a portion of the body-web or band of a carrier, such portion being located at one side of the pocket 65 which is about to be described. 2 is the side-wall at such side of the said pocket. 3 in Figs. 3 and 4 is the pocket-back; 4 is the pocket-front, it being as stated integrally joined to the pocket-back at the bottom of 70 the pocket. 5 is the other side-wall of the pocket, and 6 is a portion of the body-web or band next adjoining the side-wall 5. In Figs. 1 and 2, 7 is a cover-flap of usual character, and 8, 9, are fastening devices of usual 75 character, applied respectively to the pocket-front and cover-flap, and designed to secure the cover-flap when the latter has been closed down over the pocket.

As stated previously herein, the side-wall 80 web-portions 2 and 5 are free at their lower ends or edges, as woven. This is illustrated in Figs. 3 and 4, which show a pocket-web before the tucking-in of the lower portions of the said side-wall web-portions, and before the application of the cover-flap. As stated, also, the proportions of these side-wall web-portions are such as to permit the pocket-front 4 to stand out from the pocket-back 3 to the extent necessary to produce a 85 pocket of the desired internal capacity. In completing a pocket, the lower portions of the side-wall web-portions are tucked inward between the pocket-front and pocket-back, as indicated by Figs. 1 and 2, and the 90 tucked-in portions are secured by fastenings, in this instance stitches 10, 10, Fig. 1, engaging with the pocket-front, the tucked-in portions, and the pocket-back. In addition, when a cover-flap, as 7, is employed, it is 95 100 suitably applied and connected with the pocket.

In weaving the pocket-web shown in Figs. 3 and 4, the portion 1 of the body-web or band first is woven of the required thickness. On arriving at the point at which side-wall 2 should spring from the said body-web or band, certain of the warp-

threads embodied in the said portion 1 of the body-web or band are left idle while the remainder of such warp-threads are interwoven with weft-thread or filling to form 5 a separate ply having upper and lower selvages. The weaving of this separate ply with the upper and lower selvages is continued until a side-wall web-portion 2 of dimensions which will permit the pocket- 10 front to stand out at the required distance from the pocket-back has been produced. A continuation of the separate ply forming the side-wall web-portion 2 forms also the pocket-front 4. The pocket-front 4 and 15 pocket-back 3 are woven concurrently, by causing the weft-thread or filling to pass first from the edge of the web at which the open mouth of the pocket is located, through the warp-threads of the said separate 20 ply, then back through the warp-threads which were left idle during the weaving of side-wall web-portion 2 to the starting edge of the web, and then reversely through the latter warp-threads and back 25 through those of the separate ply to the starting edge again, and so on as before. This mode of weaving produces a pocket-front and pocket-back which are united integrally at the bottom of the pocket in the 30 weaving, by means of the weft-thread passing from the ply constituting the pocket-front to the ply constituting the pocket-back, and vice versa, and as usual, also, it provides the pocket-front and pocket-back, 35 respectively, with selvages at the open mouth of the pocket. The weaving of the pocket-front and pocket-back concurrently is continued until they have been produced of the required dimensions for a pocket of the desired 40 width from side to side. Preferably they will be equal, although to a certain extent a greater number of picks of weft-thread or filling may be incorporated in well-known manner in the pocket-front than in the

pocket-back. Then the weaving of the 45 pocket-back is discontinued, while the weaving of the separate ply is continued to form the side-wall web-portion 5 with upper and lower selvages. When the web-portion 5 has been produced of the required dimensions, the said separate ply, and that constituting the pocket-back, are bound together in the weaving, and the weaving of the portion 6 of the body-web or band-portion is proceeded with. The next succeeding pocket, 50 of the carrier-web as woven in a loom, is produced by a repetition of the described procedure. The carrier-web formed with a succession of pockets will, as usual, be divided up into lengths comprising one or 55 more pockets, as desired.

What is claimed as the invention is,—
1. The improved woven pocketed carrier having a pocket that is formed with the pocket-front integrally joined to the pocket-back at the bottom of the pocket, and united laterally with the pocket-back by means of side-wall web-portions which, as woven, are free at their lower ends, with the said lower ends tucked inwardly between the pocket-front and pocket-back and fastened in place. 65

2. The improved woven pocketed carrier having a pocket that is formed with the pocket-front integrally joined to the pocket-back at the bottom of the pocket, and united laterally with the pocket-back by means of side-wall web-portions which, as woven, are free at their lower ends, with the said lower ends tucked inwardly between the pocket-front and pocket-back and secured in place 70 by stitches passing through the pocket-front, tucks, and pocket-back. 75

In testimony whereof I affix my signature in presence of two witnesses.

VICTOR H. JENNINGS.
